UNITED STATES PATENT OFFICE.

GUSTAVE F. KOLB, OF MOUNT VERNON, NEW YORK, ASSIGNOR TO THE MAUSER MANUFACTURING CO., OF NEW YORK, N. Y., A CORPORATION
OF WEST VIRGINIA.

DESIGN FOR A SPOON.

No. 38,655.

Specification for Design.

Patented July 9, 1907.

Application filed June 4, 1907. Serial No. 377,269. Term of patent 3½ years.

To all whom it may concern:

Be it known that I, GUSTAVE F. KOLB, a citizen of the United States, residing at Mount Vernon, Westchester county, State of New York, have invented a new, original, and ornamental Design for a Spoon, reference being had to the accompanying drawing, forming part thereof.

I claim:

The ornamental design for a spoon, as shown.

GUSTAVE F. KOLB.
